UNITED STATES PATENT OFFICE.

ELMER A. DE KARSKE, OF MILWAUKEE, WISCONSIN.

DISPLAY RACK.

Application filed December 12, 1924. Serial No. 755,459.

This invention relates to display racks.

Objects of this invention are to provide a display rack which will support articles on exhibition on a shelf or suitable support and at such an angle as will correctly and attractively display the same.

Further objects are to provide a display rack which is made from a single piece of sheet material, which is readily attached to the end of a shelf or other support, which is provided with a brace for holding the device in its correct angular position, and which is provided with means for engaging the shelf or support to lock the device in place.

Further objects are to provide a display device which may be readily stamped from sheet metal in a simple and cheap manner, and in which an attractive appearance is attained.

An embodiment of the invention is shown in the accompanying drawings, in which:—

Figure 1 is a plan view of the device as it appears when applied to the support.

Figure 2 is a side view of the structure shown in Figure 1 showing the support in section.

Referring to the drawings, it will be seen that the display rack comprises a piece of sheet metal, which is provided with a top portion 1 adapted to extend substantially horizontally from the edge of the shelf 2, as shown in Figure 1. This top portion is provided with a downwardly turned pin or burr 3 which constitutes a fastening means adapted to be forced into the shelf and such top portion preferably consists of two outer arms leaving an intermediate central portion. This intermediate portion is punched downwardly from the top portion and provides a brace 4, and the end of the brace is rounded to form a cam, as indicated at 5, and is adapted to bear against the vertical face of the shelf or support, and to thus rigidly brace or hold the device in an outwardly extending position.

The body portion 6 of the display rack constitutes an integral continuation of the top portion and brace, and is preferably slightly enlarged at its central portion and provided with scalloped or otherwise ornamentally shaped edges, and with an upturned lip or ear 7 adapted to engage the heel of the shoe, or other article to be displayed, and hold same in position. If desired, this body portion may be provided with one or more punched openings 8 in order to lighten it and enhance its attractiveness. The lower part of the

body portion 6 is preferably slightly enlarged to provide marginal portions 9 preferably joined by a transverse member 10 to strengthen such portions and to maintain them in alinement.

When it is desired to position the device, it is merely necessary to press the tongue 3 into the upper portion of the shelf or support 2 with the brace 4 contacting with the vertical face of the shelf. This holds the display rack in the downwardly and outwardly extending position, shown in Figure 2, and correctly positions it for the reception and display of a shoe, or other article. The shoe is placed upon the slanting portion of the rack with its heel resting against the lip 7 and with the toe portion resting upon the open work lower end of the body portion.

It will further be seen that a display rack has been provided which is of extremely simple and strong construction, which may be easily applied to a shelf or other support, which is braced and held outwardly therefrom in a rigid and substantial manner, and which is of attractive and pleasing appearance.

While the drawing illustrates a rack which is particularly designed for use in displaying a shoe, obviously the rack may be used to display any articles to be vended, as for example canned goods, boxes, or the like. In some instances, the marginal portion 9, or outer end of the rack, may be bent upwardly to form a horizontal supporting shelf. It will also be understood that while I have shown only one tongue 7 upset from the body of the shelf, a series of such tongues in some cases may be formed for holding various articles.

The primary feature is the arrangement of the brace 4 with its circular cammed end operating in conjunction with the tongue or burr 3, whereby the shelf is rigidly supported.

Although the invention has been described in considerable detail, it is to be understood that the invention may be variously embodied and is, therefore, to be limited as claimed.

I claim:—

A display rack formed of sheet metal and integral throughout and comprising a downwardly and forwardly extending portion, an approximately horizontal top member having a prong struck downwardly and forwardly therefrom and adapted to project into a horizontal portion of a support having approximately horizontal and vertical faces, a

brace extending rearwardly from the body portion below the top portion and approximately paralleling the top portion of the device and having a terminal portion adapted to bear against the vertical face of the support, said terminal portion acting as a fulcrum during attachment of the device, and a

heel engaging tongue struck upwardly from the body portion.

In testimony that I claim the foregoing I have hereunto set my hand at Milwaukee, in the county of Milwaukee and State of Wisconsin. ¹⁰
